UNITED STATES PATENT OFFICE.

CULLIN W. REED, OF CHAGRIN FALLS, OHIO.

DESIGN FOR FOOT-SCRAPERS.

Specification forming part of Design No. 7,489, dated June 9, 1874; application filed May 13, 1874.
[Term of Patent 7 years.]

To all whom it may concern:

Be it known that I, CULLIN W. REED, of Chagrin Falls, Ohio, have invented a new and original Design for a Frame for Foot-Serap-ers, of which the following is a specification:

This invention relates to a novel design of a frame or holder for receiving and confining in place the brushes or scrapers of a foot-scraper.

The invention consists of a rectangular or square frame, composed of vertical side walls, a rear wall and a front wall of a height less than the side walls, and horizontal or lateral flanges, projecting inwardly, for supporting the frames composing the scraper or brushes of the foot-scraper. At the front of the frame is a dirt-receptacle, of a waved or corrugated form, for receiving the dirt from the feet and brushes.

In the accompanying drawing, Figure 1 is a perspective view of my frame; Fig. 2, a longitudinal central section.

The frame or holder is composed of vertical side walls A A, a rear vertical wall, B, and a

front wall, C, the latter walls being of a height less than the side walls. From the side, and front, and rear walls project inwardly horizontal flanges D, for supporting the scrapers or brushes composing the foot-scraper. At the front of the frame, extending outwardly, is a dirt-receptacle, E, which is constructed of a waved or corrugated form, for receiving the dirt scraped from the shoes, and from the side walls project outwardly the flanges F, which are of an ogee form, and are provided with openings a, whereby the frame may be secured to a suitable base-piece. The frame is preferably cast of a single piece of metal.

I claim as my invention—

The design for a foot-scraper frame, substantially as described, and illustrated in the accompanying drawing.

CULLIN W. REED.
